CLAIM

The ornamental appearance for a hair dryer paddle brush, as shown and described.

DESCRIPTION

FIG. 1 is a perspective view of a hair dryer paddle brush, showing our new design;

FIG. 2 is a front elevation view of FIG. 1;

FIG. 3 is a rear elevation view of FIG. 1;

FIG. 4 is a left side elevation view of FIG. 1;

FIG. 5 is a right side elevation view of FIG. 1;

FIG. 6 is a top plan view of FIG. 1; and,

FIG. 7 is a top plan view of FIG. 1.

The broken lines in the drawings depict portions of the hair dryer paddle brush that form no part of the claimed design.

1 Claim, 4 Drawing Sheets
